UNITED STATES PATENT OFFICE.

VINCENT TUMMINELLO, OF CEFALÙ, ITALY.

CUFF-BUTTON.

1,273,204.

Specification of Letters Patent. Patented July 23, 1918.

Application filed December 22, 1917. Serial No. 208,431.

To all whom it may concern:

Be it known that I, VINCENT TUMMINELLO, a subject of the King of Italy, residing at Cefalù, in the Province of Palermo, Italy, have invented certain new and useful Improvements in Cuff-Buttons; and I do hereby declare the following to be a full, clear, and exact description of the invention, such as will enable others skilled in the art 10 to which it appertains to make and use the same.

This invention is directed to improvements in cuff buttons, and has for its object to provide an article of this character which 15 is formed from a single length of metal.

A further object of the invention is to provide an article of this type formed from a single length of metal, bent so as to provide distinctive and ornamental heads or 20 buttons.

A still further object of the invention is to provide a link button having heads integrally formed with the link or shank.

With these and other objects in view, this 25 invention resides in the novel features of construction, formation, combination and arrangement of parts to be hereinafter more fully described, claimed and illustrated in the accompanying drawing in which:—

Figure 1 is a perspective view of one form 30 of the button.

Fig. 2 is a similar view of a slightly modified form of the invention.

Fig. 3 is a similar view of another modified form of the invention.

Fig. 4 is a similar view of still another modified form.

Fig. 5 is still another modified form of the invention.

Fig. 6 is a vertical longitudinal central 40 sectional view through a modification similar to that shown in Fig. 5, except that the portions of the shank which pass through the convolutions touch the inner faces of the 45 convolutions.

Referring particularly to Fig. 1, 1 designates the shank of the button, which terminates at its ends in coils 2 and 3, which constitute heads or buttons, the coils 2 being 50 slightly larger than the coils 3. By making the coils 3 smaller than the coils 2 will permit the same to more readily pass through the button-holes of the cuff.

The convolutions of the coils are pressed 55 tightly together in any suitable manner so

as to provide rigid buttons or heads. The terminal 4 of the coil 2 is bent inwardly and transversely, and in contact with the adjacent parts of the convolutions and has its end in a plane with the outer sides of the 60 innermost coil, while the terminal 5 of the coil 3 is bent outwardly and transversely, and also in contact with the adjacent convolutions of the associated coil, and has its end in a plane with the sides of the outer- 65 most coil.

Referring now to Fig. 2, the shank 6 terminates at its end in coils 7 and 8, the former being larger than the latter. The innermost convolutions of the coils 7 have 70 their ends bent outwardly and into engagement with the adjacent parts of the remaining helices. The coils 8 are arranged in the same manner as the coils 3 of the preferred 75 form of the invention.

In Fig. 3 the shank 10 has a greater number of larger coils 11, and the terminal 12 of which is arranged in the same manner as the terminal of the coil 2, while the terminal 13 of the coils 14 are directed inwardly under the adjacent end of the shank 10. 80

In Fig. 4 the shank 15 has its coils 16 and 17 so bent that the respective terminals 18 and 19 thereof are both bent inwardly and transversely of the convolutions of the coils. 85

In Fig. 5 of the drawing the shank 20 terminates at its ends in convolutions 21, which are bent so as to provide conical heads or buttons 22. The terminals of the convolutions 23 are bent to extend transversely 90 through the convolutions.

In the sectional view, Fig. 6, there is shown a form similar to the form shown in Fig. 5, with the exception that the outer ends of the shank 20' are bent to lie against 95 the inner portions of the coils of the heads 21', thereby securely bracing the heads and shank and providing a rigid structure, these portions of the shank being shown at 24.

It will be noted that in all of the forms 100 of the invention one set of coils is slightly greater in size than the other set, except those shown in Fig. 6, wherein the heads are of the same size. The convolutions of the coils are pressed into close contact with each 105 other to produce rigid structure without any openings or creases to catch in the clothing.

What is claimed is:

1. A cuff button comprising a shank, the terminals of the shank being formed with 110

helix coils, the end of the outermost of each coil being extended transversely through the coils.

2. A cuff button formed from a single length of suitable wire and including a shank and a plurality of helix coils at the ends thereof, said coils being of various diameters to form conical heads.

3. A cuff button formed from a single length of suitable wire and including a shank, a plurality of helix coils formed at

each end of the shank and of various diameters to form conical heads, the outer portions of the shank passing through the coils and bearing against the inner faces of one side thereof, the ends of the outermost coils being turned transversely inwardly of the coils, the outermost coils being smaller than the other coils and closing the outer ends of the heads.

In testimony whereof, I affix my signature.

VINCENT TUMMINELLO.

Copies of this patent may be obtained for five cents each, by addressing the "Commissioner of Patents, Washington, D. C."
